UNITED STATES PATENT OFFICE

129,618

DESIGN FOR AN AUTOMOBILE

Ralph S. Roberts, Grosse Pointe Farms, Mich.,
assignor to Briggs Manufacturing Company,
Detroit, Mich., a corporation of Michigan

Application June 28, 1941, Serial No. 101,775

Term of patent 14 years

To all whom it may concern:

Be it known that I, Ralph S. Roberts, a citizen of the United States, residing at Grosse Pointe Farms, county of Wayne, State of Michigan, have invented a new, original, and ornamental Design for an Automobile, of which the following is a specification, reference being had to the accompanying drawings, forming a part thereof, in which

Fig. 1 is a perspective view of an automobile illustrating my new design, looking toward the left front thereof.

Fig. 2 is a perspective view of the automobile of Fig. 1, looking toward the right rear thereof.

Fig. 3 is a side elevational view of the automobile of the preceding views; and

Fig. 4 is a view similar to Fig. 3 but showing the top in raised or elevated position.

I claim:

The ornamental design for an automobile, as shown.

RALPH S. ROBERTS.
